(**) Term: **14 Years**

(57) **CLAIM**

(21) Appl. No.: **29/323,880**

The ornamental design for numbered pin for quilting or sewing, as shown and described.

(22) Filed: **Sep. 2, 2008**

DESCRIPTION

(51) **LOC (9) Cl.** 02-07
(52) **U.S. Cl.** **D3/28**

FIG. 1 is a perspective view of a numbered pin for quilting or sewing, showing my new design system;

(58) **Field of Classification Search** D3/18-29;
66/116-118; 223/102; D7/683, 684; D11/47,
D11/61, 206, 207; D15/78; 24/13, 711.4;
411/923

FIG. 2 is a front elevational view of the invention, the rear view being a mirror image thereof;

See application file for complete search history.

FIG. 3 is a left-side elevational view of the invention, the right-side elevational view being a mirror image thereof;

(56) **References Cited**

FIG. 4 is a top plan view of the invention; and,
FIG. 5 is a bottom plan view of the invention.

U.S. PATENT DOCUMENTS

D48,659 S * 2/1916 Davis D11/47
D125,868 S * 3/1941 Yucassovich D3/28
